UNITED STATES PATENT OFFICE.

DAVID F. BLACK, OF BROOKLYN, NEW YORK, ASSIGNOR TO HIMSELF AND THOMAS FOLDBERG, OF PRINCETON, NEW JERSEY.

FIRE-ESCAPE.

SPECIFICATION forming part of Letters Patent No. 275,121, dated April 3, 1883.

Application filed November 9, 1882. (No model.)

To all whom it may concern:

Be it known that I, DAVID F. BLACK, of Brooklyn, in the county of Kings and State of New York, have invented a new and Improved 5 Fire-Escape, of which the following is a full, clear, and exact description.

The object of my invention is to provide a new and improved fire-escape which can be adjusted at various heights, and which is provided with side bridges which can be extended to the windows of the houses; and to this end it consists in the peculiar construction and arrangement of parts, as hereinafter fully described, and pointed out in the claims.

Reference is to be had to the accompanying 15 drawings, forming a part of this specification, in which similar letters of reference indicate corresponding parts in all the figures.

Figure 1 is a longitudinal elevation of the 20 fire-escape, showing it erected. Fig. 2 is an end elevation of the same, showing it erected and the side bridges swung out and the extensions drawn out. Fig. 3 is a longitudinal elevation of the same, showing it lowered and 25 swung in the horizontal position. Fig. 4 is a plan view of the wagon-platform on which the extensible ladder is pivoted, the ladder being removed. Fig. 5 is an enlarged detail sectional elevation of the same on the line $x-x$, Fig. 4, 30 showing the latch and the windlasses. Fig. 6 is a longitudinal sectional elevation of the base section of the extensible ladder, the second section being shown partly raised within the base section. Fig. 7 is a sectional plan view 35 of the base section of the ladder on the line $y-y$, Fig. 8, the swinging bridge being shown raised or swung upward. Fig. 8 is a longitudinal sectional elevation of the base section 40 of the extensible ladder, the swinging bridge being shown in section.

The extension-ladder is formed of three sections, A' , A^2 , and A^3 , of which the section A' is the base section, into which the section A^2 passes, and the section A^3 passes into the section A^2 . If desired, the ladder may be formed 45 of more than three sections. At the middle of its length the base section, A' , is provided on opposite sides, at one of the longitudinal edges, with pivots a , which pivots are journaled in 50 the upper ends of standards B on a wagon-

platform, B' , on which pivots the said base section can swing. When the ladder is not in use it is in a horizontal position, and the upper end of the base section rests on the upper end of a standard, B^2 , on the wagon-platform B' . 55 At its upper end, and on the side which faces downward when the ladder-section A' is in a horizontal position, I have provided a headed stud, b , which passes into a recess, b' , in the top of the standard B^2 , and is locked in position by a forked bolt, b^2 , which can be moved longitudinally by means of suitable levers pivoted to the same, whereby the upper end of the base section, A' , can be locked on the upper end of the standard B^2 . 65

A rod, c , arranged for projecting from the top of the standard B^2 , is attached to a hand-lever, c' , pivoted to an arm of the standard B^2 . The said rod c and the lever c' are used to throw the upper end of the base section, A' , 70 upward when the ladder is to be swung from a horizontal position, or, in other words, to start the ladder. The upper end of the standard B^2 is recessed, so as to conform to the contour of the cross-section of the base section, 75 A' , and to prevent lateral movement of the upper end of the said base section of the ladder when the same is in a horizontal position. I have also provided springs c^2 in the upper end of the standard B^2 , for the purpose of assisting in throwing the upper end of the base 80 ladder-section, A' , upward. An arm, C , projects from that side of the base ladder-section, A' , which is downward when the base section, is in the horizontal position, and to the outer 85 end of the said arm a cable, rope, or chain, C' , is attached, which passes over a pulley, c^3 , and is wound on a windlass-drum, C^2 , within the standard B^2 , and provided with a crank-handle, C^3 . A rope, chain, or cable, D , is attached 90 to a ring or loop, D' , at the lower end of the same surface of the base ladder-section, A' , from which the arm C projects, and the said rope D passes over the pulley c and a pulley, c^4 , and is wound on a windlass-drum, D^2 , provided 95 with a crank-handle, D^3 . The lower end of the surface of that side of the base ladder-section A' which is at the top when the section is in the horizontal position is rounded off or beveled, and is provided with an aperture, d , 100

for receiving a horizontally-sliding latch-bolt, d' , which is automatically forced into the aperture d by a spring, d^2 , when the ladder-section A' is in a vertical position, whereby the 5 said ladder-section will be locked in this position. If the section A' is to be swung into the horizontal position, the bolt d' must first be withdrawn from the aperture d by means of the lever d^3 , which is connected with the 10 sliding bolt d' . Ropes or chains E are attached to the lower ends of the ladder-section A' and pass over pulleys T, journaled near the upper end of the section A', the lower ends of which 15 ropes are attached to windlass-drums G, provided with ratchet-wheels H and crank-handles I, one windlass being provided at each of two opposite sides of the section A'. By winding the cables E on the windlass-drums G the ladder-section A' is raised. In the same manner 20 the ladder-section A' can be raised out of the section A' by means of similar windlasses. The ladder-section A' is provided on opposite sides with rack-bars J, having downwardly-projecting teeth, against which pawl-bolts J' 25 are pressed by springs J², which pawl-bolts are provided with upwardly-projecting handles J³, projecting from the top of the ladder-section A', by means of which handles the pawl-bolts can be withdrawn to permit of lowering the ladder-section A'.

A spring-pawl, K, rests against the teeth of each ratchet-wheel H, and can be pressed from the same by means of a hand-lever, K', pivoted to the side of the base ladder-section, A'. The 35 pawls K automatically lock the windlass-drums in position; but when the sections are lowered the spring-pawls must be disengaged from the ratchet-wheels H to permit the crank-handles I to rotate in the inverse direction. 40 This is accomplished by drawing the upper ends of the levers K' in the direction of the arrow a' in Fig. 2. The upper ladder-sections, A² and A³, are also provided with like devices, and are also provided with rack-bars J.

45 The ladder-sections A' and A² are provided with two ladders, M, on the sides that are at right angles to the house from which the persons are to be rescued, and the topmost section is provided with two ladders, M' M', which 50 are partly on the sides parallel with the house and partly on the sides at right angles to the same. In place of these ladders, circular staircases or circular ladders can be provided, and, if desired, the said staircases or ladders may 55 be provided with rope handles to prevent the persons being saved from falling.

The base ladder-section, A', is provided on each side which is parallel with the side of the house from which the people are to be rescued—60 or, in other words, parallel with the horizontal sides of the wagon-frame—with a longitudinal recess, O, adapted to receive a swinging bridge, P, which is pivoted in the said recess at the upper end of the base ladder-section, A', which 65 bridge is adapted to swing upward and outward from the lower part of the base ladder-

section, A', its turning-point being at the upper part of the base ladder-section. Two bars, P', which are pivoted to the under side of the bridge P, about one-third of the length of the 70 bridge from the side of the base ladder-section, A', have their lower ends pivoted on crank-arms Q on a horizontal transverse shaft, R, journaled in the section A', parallel with the longitudinal side of the wagon-frame, which 75 shaft R is provided with a crank-handle, R'. When the bridge P is folded within the recess the crank-arms Q of the shaft R project downward and rest flat against the base of the recess O, and the arms P also rest flat against 80 the base of the recess O. If the crank-handle R' is turned to project upward, the crank-arm Q will be swung upward on a half-circle until it again rests on the base of the recess O in the position shown in Figs. 2 and 8. The rods 85 P' are also swung upward and swing the bridge P upward into a horizontal position. The weight of the bridge causes the said rods P' to press the crank Q against the base of the recess O, whereby the movement of the crank in 90 the reverse direction of the arrow a^2 (see Fig. 2) is prevented, and as its movement in the direction of the arrow is prevented by the weight of the bridge, it will be held in this position until the said bridge is raised, the rods 95 P' thus forming a brace to hold the bridge P in the horizontal position.

The bridge P is provided with a longitudinally-sliding central extension-section, S, which is suitably guided and held by tongues 100 and grooves in the bridge P, as shown in Figs. 7 and 8. The bridge P and the extension S are provided with railings, preferably made of ropes and upright rods, as shown in Fig. 2. Two ropes or cables, T, are attached to the inner end of the extension-section S of the bridge P and pass over horizontal pulleys T', near the outer end of the bridge P, and from there pass through suitable grooves in the said bridge P over the pulleys T², mounted on the pivot of 105 the bridge P. A rope or cable, U, also attached to the inner end of the sliding extension-section S, passes directly from the inner end of the said section S over a pulley, T². The ropes or cables T and U are attached to drums 110 U', mounted on a shaft, V, provided with a crank-handle, V'. The ropes are attached to and wound on the drums in opposite directions—that is, when the ropes T are wound on the drums the rope U is unwound, and, vice 115 versa, when the rope U is wound on the drum the ropes T are unwound. For instance, by turning the crank-shaft V' in such a direction that the ropes T are wound on the drums the inner end of the sliding extension section S will be 120 moved toward the outer end of the bridge P—that is, the sliding section will be projected from the end of the bridge P. By turning the crank V' in the inverse direction the rope U is wound on the drum and the ropes T are unwound and sliding section S is drawn into the 125 bridge P. The base section, A', is provided 130

with projecting platforms or balconies W for the attendants who turn the crank-handle R'. The sections A² and A³ are provided with swinging bridges P and sliding extension-sections S in the same manner as has just been described. The upper ends of the ladder-sections are preferably provided with railings to prevent the attendants and others from falling.

The operation is as follows: When not in use the fire-escape is held in a horizontal position, as shown in Fig. 3, and in this position it is transported to the fire and is properly located in front of the building. Then the headed stud b is released from the latch-bolt b², the lever c is pressed downward at its outer end to cause the rod c to throw the upper end of the ladder-section A' upward, and then the cable D is wound on the windlass-drum D², whereby the base ladder-section, A', will be swung into a vertical position, the lower end of the base ladder-section swinging downward and the upper end upward. The latch-bolt d' automatically snaps into the aperture d in the lower end of the base ladder-section, A', and locks the same in a vertical position. Then the sections A² and A³ are raised by winding the several ropes or cables E on the windlasses G. According to the height of the building from which persons are to be rescued, the fire-escape must be elevated more or less. If persons are to be rescued from a building, one or more of the bridges P are swung upward and outward toward the building, and if they are not of sufficient length to reach the building the sliding extensions S are projected from the ends of the bridges, in the manner previously described, until the ends of the said extensions rest on the window-sills, cornices, or copings of the building. The persons to be rescued can then pass from the building over the extensions S and the bridges P to the fire-escape and can climb down the ladders of the same to the ground. Then, if the fire-escape is to be lowered, the extensions S are drawn into the bridges P, the bridges are swung down into the recesses O, and the ladder-sections are successively lowered. Then the bolt d' is withdrawn, and by winding the rope C' on the windlass-drum C² the base ladder-section, A', is swung into the horizontal position, with its end resting on the standard B.

I am aware that a series of telescopic ladder-sections has heretofore been employed; and I am also aware that telescopic sections of a ladder have been provided with racks which are engaged by pawls for holding the same in any desired position, and I therefore do not claim such inventions.

Having thus fully described my invention, I claim as new and desire to secure by Letters Patent—

1. In a fire-escape, the combination, with a series of telescopic ladder-sections, each section having its side bars provided with longitudinal recesses, of bridges pivoted in the upper ends of the said recesses, and adapted to

be swung upward and outward from the sections when in use and to be swung down into the said recesses when not in use, substantially as herein shown and described. 70

2. In a fire-escape, the combination, with a series of telescopic ladder-sections having longitudinal recesses in their sides, of bridges having sliding extensions pivoted in the said recesses, and means, substantially as herein shown and described, for withdrawing the section from the said bridges and supporting the bridges in a horizontal position, as set forth. 75

3. In a fire-escape, the combination, with a series of telescopic ladder-sections, of swinging bridges, and of rods pivoted to the under sides of the swinging bridges and to the ends of cranks on shafts in the sections of the ladder, substantially as herein shown and described, and for the purpose set forth. 80

4. In a fire-escape, the combination, with a ladder-section having a recess, O, of the swinging bridge P and devices for swinging the bridge, substantially as herein shown and described, and for the purpose set forth. 85

5. In a fire-escape, the combination, with a ladder-section, of the bridge P, and the rods P', pivoted to the under side of the bridge and to the crank Q of the shaft R, having a crank-handle, R', substantially as herein shown and described, and for the purpose set forth. 90

6. In a fire-escape, the combination, with a ladder-section, of a pivoted bridge, P, devices for swinging the same, the sliding section S in the said bridge, the ropes T and U, attached to the rear end of the section S, the pulleys T' and T², the windlass-drums U', and the crank-shaft V, substantially as herein shown and described, and for the purpose set forth. 100

7. In a fire-escape, the combination, with the base ladder-section, A', of the ladder-section A², fitting within the same, the ropes E, the pulleys F, the windlass-drums G, the rack-bars J, the pawl-bolts J', the springs J², and the handle-levers J³, substantially as herein shown and described, and for the purpose set forth. 105

8. In a fire-escape, the combination, with a ladder-section, of the swinging bridges P, pivoted to the same, the cranks Q, for swinging the said bridges, and of balconies W, substantially as herein shown and described, and for the purpose set forth. 115

9. In a fire-escape, the combination, with a telescopic ladder having pivots a, of the standards B B², the arms C, the ropes C' and D, and the windlass C² D², substantially as herein shown and described, and for the purpose set forth. 120

10. In a fire-escape, the combination, with a telescopic ladder pivoted on the standards B, of the standard B², containing a sliding latch-bolt, b², and of the headed stud b on the upper end of the base-section of the telescopic ladder, substantially as herein shown and described, and for the purpose set forth. 125

11. In a fire-escape, the combination, with a

telescopic ladder pivoted on the standards B, of the standard B², of the rod c, and the lever c', substantially as herein shown and described, and for the purpose of starting the ladder when it is to be swung into vertical position.

12. In a fire-escape, the combination, with a telescopic ladder pivoted on the standards B, of the sliding spring-bolt d', fitting within an aperture, d, in the lower part of the base-sec-

tion of the ladder, and of the lever d², for withdrawing the bolt d', substantially as herein shown and described, and for the purpose set forth.

DAVID F. BLACK.
